United States Patent Office

Des. 196,205
Patented Sept. 3, 1963

196,205

TYPEWRITER OR THE LIKE

James D. Bungard, East Detroit, Mich., assignor to Dura
Business Machines, Inc., Madison Heights, Mich., a corporation of Delaware

Filed Aug. 13, 1962, Ser. No. 71,252

Term of patent 14 years

(Cl. D64—11)

Fig. 1

The essential features of the design reside in the portions shown in solid lines on the drawings.

I claim:

The ornamental design for a typewriter or the like, substantially as shown and described.
